UNITED STATES PATENT OFFICE.

JOHN VERMEULEN, OF NEW YORK, N. Y.

KNIFE-SHARPENER.

SPECIFICATION forming part of Letters Patent No. 434,366, dated August 12, 1890.

Original application filed January 14, 1890, Serial No. 336,878. Divided and this application filed April 9, 1890. Serial No. 347,229. (No model.)

To all whom it may concern:

Be it known that I, JOHN VERMEULEN, a subject of the King of Belgium, residing in the city, county, and State of New York, have 5 invented a new and Improved Knife-Sharpener, (for which I originally filed an application for Letters Patent of the United States dated January 14, 1890, Serial No. 336,878, allowed March 21, 1890, this being a division 10 of the said original application,) of which the following is a full, clear, and exact description.

The object of the invention is to provide a new and improved knife-sharpener which is 15 simple and durable in construction and specially designed to conveniently and quickly sharpen knives.

The invention consists of certain parts and details and combinations of the same, as will 20 be hereinafter fully described, and then pointed out in the claims.

Reference is to be had to the accompanying drawings, forming a part of this specification, in which similar letters of reference indicate 25 corresponding parts in all the figures.

Figure 1 is a side elevation of the improvement. Fig. 2 is a transverse section of the same on the line 22 of Fig. 1. Fig. 3 is a plan view of the improvement. Fig. 4 is a sectional side elevation of the same on the line 44 of Fig. 3. Fig 5 is an end view of a modified form of the roller. Fig. 6 is a side elevation of the same; and Fig. 7 is a sectional plan view of a modified form of the improvement. 30

The improved knife-sharpener A is provided with a suitably-constructed bed-plate B, from one end of which at the under side extends an L-shaped arm C, in which screws a screw D for securely fastening the bed-plate 35

40 B to a table or a bench.

On the top of the bed-plate B is arranged a casing E, provided with a vertically-extending slot F, into the lower part of which pass the rims of two sharpening-rollers G and G', held 45 on shafts H and H', mounted to turn in suitable bearings in the casing E and parallel with the sides of the transverse slot F. Each of the rollers G and G' has V-shaped annular ridges G² on its periphery. The outer short 50 edges of the V-shaped ridges touch at the center of the slot F, as is plainly shown in

Figs. 1 and 4, so that when a knife is inserted in the said slot F and pressed down on the rollers and drawn inward or outward this knife-edge comes in contact with the short 55 edges of the ridges of the two rollers G and G', and is thereby sharpened.

The shafts H and H' are each provided on one outer end with a toothed wheel I or I', respectively, each having V-shaped teeth 60 adapted to be engaged by a rectangular plate J, held between the two wheels and adapted to engage oppositely-arranged teeth, so as to prevent the said wheels from turning and to hold the rollers G and G' in place. The plate 65 J is secured at one end on a transversely-extending shaft K, arranged to slide in suitable bearings in the casing E, and provided at its other end with a head K', on which presses one end of spring L, held in a suitable 70 offset E', formed on the rear end of the casing E. The spring L has the tendency to press the head K' outward, thus holding the plate J in contact with the front face of the casing E, at the same time engaging the said plate 75 with the toothed wheels I and I'. When the rollers G and G' have become worn by use at a point which extends into the slot F, then the operator presses on the head K' of the shaft K, so as to shift the latter inward, thereby 80 disengaging the plate J from the notched wheels I and I'. The operator can then turn the said notched wheels the distance of one or more teeth, so that new points of the ridges G² of the rollers G and G' pass into the slot F. 85 The shafts H and H' may also be mounted to turn in bearings fitted to slide longitudinally in the casing and held adjustable by a set-screw, as shown in Fig. 7. In case the rollers are worn on their peripheries, then so as not to 90 touch in the slot, the bearings are moved inward until the rollers meet.

When the operator desires to sharpen a knife, he places the knife-blade in a vertical position, with the edge downward, and inserts 95 it in the slot F until the knife-edge rests on the V-shaped ridges G² of the two rollers G and G'. The operator then draws the knife-blade transversely several times, pressing down on it, so as to hold the knife-edge firmly 100 in contact with the V-shaped ridges of the rollers G and G' while drawing the knife for-

ward and backward. The knife is thus sharpened.

The sharpening-rollers G and G' are made of suitable material, preferably of solid steel or emery, or they may be made of a series of washers placed on the respective shaft H or H', as plainly shown in Figs. 5 and 6. In order to hold the several washers on the shaft, the latter is provided with a flattened side, and a corresponding aperture is formed in each washer.

It will be seen that the device is very simple in construction, can be cheaply manufactured, and will form an indispensable household article.

Having thus fully described my invention, I claim as new and desire to secure by Letters Patent—

1. The combination, with a casing having a transverse slot, of transverse sharpening-rollers within the casing at opposite sides of said slot and provided exterior to the casing with toothed operating-wheels, and means for locking the said wheels against turning, substantially as set forth.

2. The combination, with a casing having a transverse slot, of transverse sharpening-rollers within the casing and provided exterior to the same side of the casing with toothed operating-wheels, and a movable plate between the said toothed wheels and engaging them with its opposite ends to lock them in place.

3. In a knife-sharpener, the combination, with a casing having a transverse slot, of two rollers arranged opposite each other and extending with their peripheries into the said slot, shafts carrying the said rollers and mounted to turn in the said casing, toothed wheels secured on the shafts, a plate adapted to engage the said toothed wheels, and a spring-pressed shaft fitted to slide and carrying the said plate for moving the latter into and out of contact with the said toothed-wheels, substantially as described.

JOHN VERMEULEN.
